United States Patent Office

Des. 229,523

Patented Dec. 11, 1973

229,523

PANTS

Herman Browdy, 3906 38th St., Brentwood, Md. 20722

Filed May 26, 1972, Ser. No. 257,483

Term of patent 14 years

Int. Cl. D2—02

U.S. Cl. D2—28

The figure is a rear elevational view of pants showing my new design, the front being conventional.

I claim:

The ornamental design for pants, as shown and described.
